GASOLINE PUMP

John S. Loy, Fort Wayne, Ind.

Application November 8, 1956, Serial No. 43,702

Term of patent 14 years

(Cl. D52—2)

The figure is a perspective view of a gasoline pump showing my new design. The opposite side and rear of the gasoline pump are substantially of the same appearance as the respective side and front shown.

I claim:

The ornamental design for a gasoline pump, as shown and described.
